UNITED STATES PATENT OFFICE.

FRANCISCO CLARK, OF DURANGO, MEXICO.

SAFETY BOTTLE.

Application filed September 16, 1921. Serial No. 501,105.

To all whom it may concern:

Be it known that I, FRANCISCO CLARK, a citizen of Mexico, and a resident of Durango, Durango, Republic of Mexico, have 5 invented a new and Improved Safety Bottle, of which the following is a description.

My invention while applicable generally to containers or receptacles provided with a neck, is more particularly intended for 10 embodiment in a bottle formed of glass, earthenware, clay, or other suitable material and adapted for use for liquids and other commodities.

The general object of my invention is to 15 provide a bottle available as an original package only by reason of embodying novel features, necessitating the breakage of a part of the bottle in order to afford access to the contents so that any attempted subsequent use of the bottle may be readily detected.

Reference is to be had to the accompanying drawings, forming a part of this specification, it being understood that the drawings 20 are merely illustrative of examples of the invention.

Figure 1 is a vertical section of a bottle embodying my invention showing the same in sealed form;

30 Figure 2 is a plan view of the bottle neck, the cap being omitted;

Figure 3 is a plan view of the split ring forming the fastening connection between the bottle and cap;

35 Figure 4 is a view similar to Figure 1 but illustrating another form of the invention;

Figure 5 is a separate plan view of the cap employed in the construction shown in 40 Figure 4;

Figure 6 is a view of the glass disk employed beneath the cap in Figure 4;

Figure 7 is a plan view of the split ring similar to the split ring as shown in 45 Figure 3 and employed in the construction shown in Figure 4.

In carrying out my invention in accordance with the form shown in Figures 1 to 3 a bottle 10 of any desired design is formed 50 with a neck 11. At the exterior of said neck, I form annular beads 12, 13. The beads 12, 13 are separated to provide an annular channel 14 therebetween. The upper bead 12 preferably has its top surface 55 in the plane with the upper edge of

the neck 11 and advantageously is of less thickness than the lower bead 13, so as to be readily breakable.

The channel 14 is adapted to partially receive a split ring 15 rectangular in cross section. A similar channel 16 is formed at the interior of the depending annular flange 17 of a cap 18, said cap being made of strong material, preferably of steel.

The split ring 15 constitutes means locking the cap to the bottle. In practice a cork A or other approved stopper is forced into the bottle neck after the bottle has been filled and the split ring 15 is then placed about the neck at the channel 14 and is compressed to lie within the edges of the ribs 12, 13 or only slightly projecting beyond the same. The cover 18 is then placed in position so that the channel 16 is in register with the channel 14 and in the plane of the split ring 15 whereupon said ring is permitted to expand under its own resiliency to thereby lie partially in the channel 16 and partially in the channel 14, thus forming an effective lock between the cap and bottle neck and inaccessible.

In order to open the bottle the same is inverted and blows are delivered against the flange 17, thus causing the ring 16 to shear off or chip off the bead 12, the blows being continued about the flange 17 until the bead 12 is removed sufficiently for the cap 18 with the ring 15 therein to be slipped from the bottle neck. The mutilation of the bottle thus brought about, makes it impossible for the bottle to be used again as an original package. The ring 15 when compressed may be held by the fingers or may be restrained in the compressed form by a fine wire, string, or the like, or held by any suitable implement until the cover 18 is placed in position so that the flange 17 lies outside said split ring with the latter in the plane of the channel 16.

Referring to the construction shown in Figures 4 to 7, the neck 11^a of the bottle 10^a is formed with upper and lower beads 12^a and 13^a, corresponding essentially with the beads 12 and 13 and forming a channel 14^a therebetween.

A cap 18^a is provided having a depending annular flange 17^a presenting a channel 16^a substantially the same as in the first-described construction to receive a split ring 15^a.

In association with the cap 18^a I employ a glass disk 18^b which is of less diameter than the bottle neck at the upper flange 12^a and rests on the top of the bottle neck and 5 has its lower surface therefore in the same plane as the top of the cap 18^a. Said cap 18^a has a rabbet 18^c accommodating the edge portion of the disk 18^b. Preferably the center of the cap 18^a is open as at 18^d.

10 I would state in conclusion that while the illustrated examples constitute practical embodiments of the invention, I do not limit myself strictly to the exact details herein illustrated, since manifestly the same can 15 be considerably varied without departure from the spirit of the invention, as defined in the appended claims.

Having thus described my invention, I claim:

20 1. A container having annular beads at the exterior thereof at the open end of the container, said beads being spaced to present a channel therebetween, the bead nearest the open end of the container being breakable, 25 a cap having a depending flange presenting a channel, in position to register with the channel of the container when the cap is in position, and a resilient split ring adapted to extend about the container at the channel 30 in the latter and expandable under its own resiliency to partially enter the channel of the cap flange to thereby lock the cap in position on the bottle, said ring constituting means to break off the bead nearest the open 35 end of the container upon blows being delivered against the flange of the cap.

2. A container of the class described having spaced members forming a channel therebetween, a member near the open end 40 of the container being breakable, a cap having a depending flange formed with a channel at the interior in register with the chan-

nel of the container when the cap is in position, and a resilient split ring accommodated partly in the channel of the container and 45 partly in the channel of the cap.

3. A container, a cap therefor having a depending flange fitting outside the container at the open end, and a resilient split ring accommodated at the exterior of the 50 container and within the flange of the cap, said container having a breakable member at the open end thereof beneath which said split ring is adapted to engage, the flange of the cap being formed to partially receive said split ring in its expanded form.

4. A container of the class described having a cap formed with a depending annular flange to extend about the upper portion of a bottle neck, the said flange and the 60 bottle neck having opposed channels, a split ring accommodated in said channels, and a glass disk on top of the bottle neck beneath the cap.

5. A container of the class described having a cap formed with a depending annular flange to extend about the upper portion of a bottle neck, the said flange and the bottle neck having opposed channels, a split ring accommodated in said channels, and a 70 glass disk on top of the bottle neck beneath the cap, said cap having a rabbet accommodating the edge portion of the disk.

6. A container of the class described having a cap formed with a depending annular flange to extend about the upper portion of a bottle neck, the said flange and the bottle neck having opposed channels, a split ring accommodated in said channels, and a glass disk on top of the bottle neck 80 beneath the cap, said cap having a rabbet accommodating the edge portion of the disk, the central portion of the cap being open.

FRANCISCO CLARK.
